US0D1071725S

(12) **United States Design Patent** (10) **Patent No.:** **US D1,071,725 S**
(45) **Date of Patent:** **** Apr. 22, 2025**

(54) **LID FOR PACKAGING**

(71) Applicant: **TETRA LAVAL HOLDINGS & FINANCE S.A.**, Pully (CH)

(72) Inventors: **Angelo Sorbara**, Rubiera (IT); **Rocco De Paola**, Modena (IT); **Franco Cani**, Modena (IT); **Tiziano Viani**, Bibbiano (IT)

(73) Assignee: **TETRA LAVAL HOLDINGS & FINANCE S.A.**, Pully (CH)

(**) Term: **15 Years**

(21) Appl. No.: **29/863,200**

(22) Filed: **Dec. 16, 2022**

Related U.S. Application Data

(62) Division of application No. 35/511,428, filed on Aug. 18, 2020 (U.S. filing date under 35 U.S.C. 384), and having an international filing date of Aug. 18, 2020, now Pat. No. Des. 977,964.
